UNITED STATES PATENT OFFICE.

FRANCIS A. P. STERRY, OF CANTON, MASSACHUSETTS.

MACHINERY FOR SPINNING FIBROUS MATERIALS.

SPECIFICATION forming part of Letters Patent No. 247,221, dated September 20, 1881.

Application filed January 7, 1881. (No model.)

To all whom it may concern:

Be it known that I, FRANCIS ASHER PERKINS STERRY, of Canton, in the county of Norfolk and State of Massachusetts, have invented 5 a new and useful Improvement in Machinery for Spinning Fibrous Materials; and I do hereby declare the same to be described in the following specification and represented in the accompanying drawings, of which—

10 Figure 1 is a front elevation, and Fig. 2 a transverse and vertical section, of a ring-spinning-frame spindle and its bolster and step-rails as provided with my invention, the nature of which is fully defined by the claims at 15 the end of this specification. Figs. 3 and 4 are hereinafter described.

In such drawings the spindle is shown at A, the bolster at B, the step-supporter at C, the step at D, the step-supporter cover at E, the 20 step-rail at F, the bolster-rail at G, and the whirl at H, all being arranged as represented.

There is combined with or fixed to the whirl, and extended above it, in manner as shown, 25 an oil-receiving cup, I, which surrounds the spindle concentrically, and at top has a lip or flange, a, projecting inward from it nearly to the bolster B, which extends through and projects below the latter rail and into the oil-cup, the bearing for the spindle in the bolster being continued through such bolster and down 30 into the cup. The lip a inclines downward from the top of the cup to the throat or spindle-opening of the cup, and is wholly outside of any part of the bolster, the lip forming to 35 the throat or spindle-opening a conical trough or mouth, as shown at b, to receive oil and carry it to the throat, from whence it passes into the cup, the cup being placed on the spindle at a sufficient distance from the rail—viz., 40 about three-quarters of one inch—to admit of the introduction of oil therein from the spout of an oiler. The lip or flange a of the mouth inclines downward, as shown, in order for such lip to operate to the best advantage as a means 45 of preventing oil from being thrown out of the cup by centrifugal force when the cup may be in rapid revolution with the spindle.

The bolster has within it a tubular bushing, b', having notches c in its upper end, or projections d extending up from it, such being as 50 shown in Figs. 3 and 4, the former of which is

a top view, and the latter a side view, of the said bushing. The step is similarly notched or provided with projections, such notches or projections serving to prevent oil from being discharged by centrifugal force from the upper part of the bolster or step carrier or supporter while the spindle may be revolving.

By having the whirl combined with and attached to the oil-cup, such whirl constitutes the 60 bottom of the cup.

The bolster bearing—that is, the part of the bolster against which the spindle bears—by being extended into the oil-cup becomes readily lubricated throughout while the spindle may 65 be in revolution; and by having the bolster-bearing extended some distance below and the oil-cup disposed at a distance, as described, from the bolster-rail, access can easily be had to the cup to supply it with oil through its 70 mouth and by means of an oil-feeder.

The step is arranged within a supporter, which is chambered, as shown at C, to hold oil and to receive the step, which is simply dropped into the oil-chamber. On raising the cover on 75 the spindle and off the step-supporter the latter may be supplied with oil when such may be necessary.

I would observe that I am well aware that 80 an oil-cup has been fixed on a spindle and extended up within the bolster and its rail, and that such bolster has been provided with a trough extending from it above its supporting-rail, and furnished with an educt or passage leading from it (the said trough) down to the 85 bore of the bolster, whereby the oil for supply of the cup had to pass into and down through the bolster before reaching the cup; also, that the said bolster was extended above the rail, and had on its upper part its bearing for the 90 spindle, there being in the bore of the bolster and below such bearing a helical groove to convey oil from the cup up to the bolster-bearing, to all of which I make no claim. My improvement differs from such in having the bolster-bearing extending below the bolster-rail and into the oil-cup, and in having the latter arranged so far below the said rail as to admit of oil being readily introduced into the mouth of the cup by an oiler, with its spout 95 below the rail. Furthermore, my oil-cup has a trough-shaped mouth to receive oil, and it 100

has a lip to prevent oil from being thrown out of the cup by centrifugal force, as described.

I claim—

1. The combination, with the bolster-bearing extended below the bolster-supporting rail and with the spindle going up through such bearing, of an oil-receiving cup fixed concentrically on the spindle at a short distance below the said rail, and provided with an annular lip encompassing the bolster-bearing and uncovered thereby, and projecting inward and inclined downward from the top of the said cup, all being substantially as set forth, the lip on its upper surface constituting a conical mouth to the cup throat or opening for reception of the bolster-bearing, and on its lower surface operating, while the spindle may be in

revolution, to prevent the expulsion of oil from the cup, as explained.

2. A spindle bolster or step having its spindle-bearing provided at its upper end with one or more notches or projections, as and for the purpose set forth.

3. The oil-cup combined with and arranged above the whirl in manner substantially as shown and described, and provided at top with an annular lip or flange extending inward from such top, and inclined downward therefrom, as and for the purpose specified.

FRANCIS ASHER PERKINS STERRY.
